(57) **CLAIM**

The ornamental design for a plumbing enclosure, as shown and described.

DESCRIPTION

In a preferred embodiment, the nature of this product is as a plumbing fixture in the form of a shower enclosure which is primarily useful for washing the body parts of humans.

FIG. 1 is a right, top, front perspective view of a plumbing enclosure embodying my new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a rear elevational view thereof; and,

FIG. 7 is a bottom plan view thereof.

The broken line representations of a flange in FIGS. 1-4 and 7, and of seams in FIGS. 1 and 3, are for the purpose of illustration only, and form no part of the claimed design.
